UNITED STATES PATENT OFFICE.

CLARENCE HAINES LAUERMAN, OF GALESBURG, ILLINOIS.

GALVANIZED-IRON VENTILATOR.

Application filed August 15, 1922. Serial No. 582,064.

To all whom it may concern:

Be it known that I, CLARENCE H. LAUERMAN, a citizen of the United States, residing at Galesburg, in the county of Knox and

5 State of Illinois, have invented a new and useful Galvanized-Iron Ventilator, of which the following is a specification.

This invention relates to ventilators and aims to provide a novel form of ventilator 10 which will operate to accomplish its purpose regardless of the direction in which the wind is blowing.

Another object of the invention is to provide a ventilator of this character including stationary louvers which have tapered ends to create a draft through the ventilator proper.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawings:

Figure 1 is a side elevational view of a 30 ventilator constructed in accordance with the invention.

Figure 2 is a plan view thereof.

Figure 3 is a bottom plan of the ventilator.

35 Figure 4 is a longitudinal sectional view through the ventilator.

Figure 5 is a sectional view taken on line 5—5 of Figure 4.

40 Figure 6 is an enlarged detail view disclosing the connection between adjacent louvers.

Referring to the drawings in detail, the reference character 5 designates the body portion of the ventilator which is preferably 45 tubular in formation to be positioned over a suitable vent pipe to which the device is to be secured.

Secured to the tubular body portion at 50 points adjacent to the upper end thereof are the upwardly extended supports 6 which are bolted to the inner surface of the body portion 5 as at 7 and have their upper ends extended at right angles as at 8 providing 55 means to secure the deflecting head 9 to the tubular body portion.

This deflecting head 9 is formed with a

circumferential flange 10 adapted to rest on the right angled portions of the support 6, where the same is bolted to the supports as by means of the bolts 11. The crown of 60 the ventilator is indicated at 12 and is formed with an inclined surface to direct water downwardly to a point remote from the spaces between the support 6, preventing moisture from entering the tubular body 65 portion 5.

Disposed in spaced relation with the body portion 5 is a collar 13 which has its upper end extended inwardly at 14 to direct air towards the crown 12 on its passage through 70 the ventilator to increase the suction or draft through the ventilator. Connected to the body portion 5 are the louvers 15 and 16, the louvers 15 having their contracted 75 extremities disposed adjacent to the upper end of the body portion 5, while the louvers 16 have their contracted portions extended downwardly as clearly shown by Figure 1 of the drawings. As shown more clearly by Figure 6 of the drawings, the louvers 15 have their side edges secured to the side 80 walls of the louvers 15 and 17, and so arranged that they will lie in spaced relation with the collar 13 to provide passageways 85 between the outer surfaces thereof and the collar 13.

The louvers 16 are shown as connected with the collar 13 as at 18 providing a support for the collar 13 and holding the same in spaced relation with the louvers 15. Secured to the supports 6, is a length of wire mesh material 19 through which the air passes, the wire mesh material acting as a 90 guard to prevent foreign matter from entering the body portion 5.

95 From the foregoing it will be obvious that as the air passes upwardly between the louvers and the collar and body portion 5, a suction is created causing air to be drawn through the body portion 5, delivering the same at the upper end of the collar, or inwardly extended portion 14 thereof.

In view of the fact that the louvers are disposed throughout the entire surface of the upper half of the body portion 5, a suction will be created at the upper end of the body portion 5 regardless of the direction in which the wind or air strikes the body portion.

Having thus described the invention, what 110 is claimed as new is:

1. In a ventilator, a tubular body portion,

a plurality of louvers secured to the body portion and having contracted lower ends, a plurality of louvers disposed between the adjacent first mentioned louvers, a collar 5 surrounding the louvers and having supporting connection with the first mentioned louvers, the second mentioned louvers being arranged in spaced relation with the collar to provide double passageways, and a deflecting member secured to the upper end of the body portion.

2. In a ventilator, a body portion, a plurality of louvers secured to the body portion

and having contracted lower ends, a plurality of louvers secured between adjacent 15 first mentioned louvers at points intermediate the side edges of the side walls thereof to provide outer and inner passageways, a collar surrounding the upper ends of the louvers, and a deflecting member secured to 20 the upper end of the body portion.

In testimony that I claim the foregoing as my own, I have hereto affixed my signature.

CLARENCE HAINES LAUERMAN.
